UNITED STATES PATENT OFFICE.

HARRY H. KELLER, OF BURNET, TEXAS.

HIGH-FREQUENCY SCREEN.

Application filed June 10, 1921. Serial No. 476,394.

To all whom it may concern:

Be it known that I, HARRY H. KELLER, a citizen of the United States, residing at Burnet, in the county of Burnet and State of Texas, have invented certain new and useful Improvements in High-Frequency Screens, of which the following is a specification.

This invention relates to an improvement 10 in sifting screens, being particularly directed to the mounting of a multiple deck screen on supports capable of high frequency vibration under suitable power application, the mounting of the screens being such as 15 to insure their movement in a true horizontal rectilinear motion to thereby avoid the objectionable arc motion ordinarily incident in the suspended type of screen or in that type supported on vertical springs.

20 The invention contemplates the mounting of the screens in multiple deck form as a unit, as for example, connected to a single frame member, and the supporting of this unit on a single point of suspension from 25 cables, wires, rods, or other elements connected to a fixture above and below the point of support and capable of being tensioned to a desired extent both above and below the point of support. The disturbing force is 30 applied at right angles to the axis of support, so that each point of support, and therefore each point throughout the screen structure, will move in a straight line in the same direction, insuring a true horizontal 35 rectilinear motion of the entire unit.

A particularly important feature of the construction, in addition to eliminating the objectionable arc motion of suspended or spring supported screens, is that the present 40 structure avoids the necessity for and provision of any bearings or bearing surfaces whatever.

In the drawings:

Fig. 1 is a view in side elevation illustrating the invention.

Fig. 2 is an end elevation of the same.

Fig. 3 is a view showing the invention applied to a scalping screen.

The improved screen structure comprises 50 a frame made up of opposed side pieces 1, of substantially rectangular shape between which the screens 2 are arranged in superimposed oppositely inclined relation. The screens are rigidly secured by means of the 55 frame members 1 to provide a rigid screen unit, and each screen may, and preferably

does, involve a screen frame 3 within which is arranged a screen section 4, beneath which there is a conveying section 5 having an outlet 6 to discharge the material upon the next 60 lowermost screen. As shown, the screens are arranged in superimposed relation in the unit, each screen being reversely inclined with respect to the next lower screen and each screen discharging at its lowermost end onto the highest end of the next 65 lower screen.

A supporting strip 7 extends transverse the respective frame members 1, said strip being arranged at mid-height said frame 70 members and being connected beyond the frame members by thru-bolts 8. These bolts constitute the point of suspension for the unit.

The screen suspending means is here 75 shown as cables 9, which at an appropriate point in their lengths are connected to the respective ends of the thru-bolts 8 as at 10. As illustrated, there are two cables for each end of the screen, though it is to be understood that the object sought is equally served by the use of a greater number of such cables. The cables are designed to be connected at their upper and lower ends to a suitable fixture, as at 11, the connection being preferably thru the medium of a turn buckle 12 or similar element, whereby the tension of the cables 9 may be adjusted at will.

One end of the screen structure, in direct 90 horizontal alignment with the point of support, is provided with a contact block 13 having a wear plate 14, designed to receive the impact of an eccentric or other element, (not shown) whereby a series of successive 95 impact jars or blows may be imparted to the support. Obviously the exact detail of the impact mechanism is not essential, and any accepted type of structure, which may impart the desired successive impacts to 100 the structure, may be used.

In Fig. 3, the invention is applied to a well known form of multiple deck scalping screen, in which the screen members 15 are connected together at the usual inclination 105 and deliver material from one screen to the next. The supporting mechanism is in this type of screen similar to that previously described, the scalping screen structure being supported on the single horizontal line from the cables 9 at 16. The impact members 13 and 14 of the previously 110

described form are applied to this type of screen, being of course arranged in direct line with the support of the screen.

It will be obvious from the above construction that when the impact or disturbing force applied to the unit is directed at right angles to the axis of support, and hence each point of support, each point of the entire screen unit, will move in a straight line in the same direction. There is therefore produced a true horizontal rectilinear motion of each point of the screen unit. The continued action is of course resultant from the vibration of the cable supports incident to the impact or disturbing force, and it is apparent that these cables may be so tensioned as to control to a greater or less extent the period of vibration, and thus the frequency of the screen movement. Obviously the cables 9 should be tensioned above and below the supporting point 10 to substantially the same tension, in order that the two rectilinear motions desired may be secured.

With this type of screen, the slope of the screens may be very flat, as by the high frequency rectilinear motion provided a substantially perfect feeding of the material lengthwise the screen is secured, even with a screen of slight inclination. Equal motion is of course obtained on all screens, and this together with the fact that the material which is oversize for each screen mesh must always pass over the whole screen length before it is discharged, insures the most accurate and perfect grading of the material submitted to the screen.

It will be noted that in the improved screen, all bearings and bearing surfaces are eliminated, the objectionable arc motion incident to the suspended or vertical spring type of the screen is avoided, and the high frequency vibration insures the most effective grading without the necessity of a pronounced inclination of the respective screens.

Claims:

1. A multiple deck screen, a tensioned supporting means arranged for unitary action and a disturbing force for said means to cause the screen to move as a unit with a true rectilinear motion.
2. A multiple deck screen and a support tensioned for unitary vibration, the screen

having a single point of connection with the support, and means for vibrating said support.

3. A multiple deck screen and a support tensioned for unitary vibration, the screen having a single point of connection with the support, and means for exerting a disturbing force on the support in line with the point of connection.

4. A series of screens secured as a rigid unit, cables tensioned for vibration, a single line of suspension between said screen unit and cables, and means for vibrating the cables.

5. A series of screens secured as a unit, cables tensioned for vibration, connections between said screen unit and cables with said connections in the same plane, and means for exerting a disturbing force on the cables in the same plane as the connections.

6. A multiple deck screen having the screens secured rigidly together as a unit, a series of cables supported at their respective ends and tensioned for vibration, and means for connecting the screen unit and cables with all said connecting means in the same horizontal plane transverse the cable support, and means for vibrating said cables, said means operating in the same horizontal plane as the connections.

7. A multiple deck screen having the screens secured rigidly together as a unit, a series of cables supported at their respective ends and tensioned for vibration, and means for connecting the screen unit and cables with all said connecting means in the same horizontal plane transverse the cable support, means for vibrating said cables, said means operating in the same horizontal plane as the connections.

8. A series of spaced supports tensioned for vibration, a multiple deck screen unit connected to said supports and moving under the vibration of the supports in a true rectilinear plane, and means for vibrating the supports.

9. The combination of a sieve, and supporting elements secured under tension and responsive to a disturbing force to impart high frequency horizontal straight line motion to the sieve.

In testimony whereof I affix my signature.

HARRY H. KELLER.
